(57) **CLAIM**

The ornamental design for an arm plate for sphygmomanometer, as shown and described.

DESCRIPTION

FIG. 1 is a front perspective view of an arm plate for sphygmomanometer showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view thereof with a joint shown in a folded position; and,

FIG. 10 is a rear perspective view thereof with the joint shown in a folded position.
